AUTOMATIC PACKAGING MACHINE

Robert E. Read, Glens Falls, N. Y., assignor to
 Union Bag & Paper Corporation, New York,
 N. Y., a corporation of New Jersey

Application June 26, 1948, Serial No. 35,326

11 Claims. (Cl. 249—4)

1

The present invention relates to improvements in packaging machine. More particularly it pertains to a machine for automatically weighing and filling bags with fibrous materials such as rockwool, asbestos, beet sugar pulp, and the like.

Heretofore, the weighing and filling of bags with such materials has been a slow, dusty and expensive manual operation, hazardous to employees. A workman, holding the bag under a discharge chute, was required constantly to jolt, tamp and force the material into the bag by hand, since such materials are of low density and difficult to compress. It was then required that additional help hand-weigh and level the filled bag to prevent over- or under-weights. It was never practical to sufficiently compress the material into the bag with the result that larger bags than necessary were required with the manual procedure.

The present invention provides a packaging machine which completely eliminates the disadvantages and inconveniences of the prior procedure. With the present machine the operator merely presses a foot switch which collapses a duckbill and permits him to slip a bag over it. Removal of his foot from the switch causes the bag to be held securely to the duckbill. The bag is then automatically filled and weighed and the material is compressed into the bag. The operator again presses the foot switch and the filled bag drops off the duckbill allowing a new bag to be placed thereon. The filled bag is then conveyed in an upright position to a sewing machine.

A general object of the present invention is to provide a packaging machine which will automatically weigh, convey into a bag, and compress fibrous or like materials, and deliver from the end of the machine a neat and compact package.

More specifically it is an object of the present invention to provide a packaging machine having a delivery hopper, a diverter for alternately feeding and diverting the product being packaged, a moving conveyor, a bag hopper and duckbill, a scale beam mechanism supporting the conveyor, hopper and duckbill and a ram cooperating with the bag hopper and duckbill to compress into the bag the product being packaged.

A further object of the invention is the provision of a packaging machine having incorporated therein a jet of fluid which will divert into an exhaust manifold, after the bag has been filled with the desired weight, any additional material which may be falling from the diverter, thus insuring more accuracy in weight.

2

It is another object of the invention to provide a packaging machine having incorporated therein a safety device which automatically diverts the flow of material from the duckbill when no bag may be held thereon or when such bag may be torn.

It is a further object of the invention to provide a packaging machine which is sturdy and durable of construction and well suited to operate in a practical and efficient manner.

Other objects of the invention will in part be obvious and will in part appear hereinafter.

The invention accordingly comprises the features of construction, combination of elements and arrangement of parts which will be exemplified in the construction hereinafter set forth and the scope of the invention will be indicated in the claims.

For a fuller understanding of the nature and objects of the invention, reference should be had to the following detailed description taken in connection with the accompanying drawings, in which:

25 Figure 1 is a perspective view of a packaging machine illustrative of the present invention;

Figure 2 is a part section, part diagrammatic view of the machine shown in Figure 1, having certain parts broken away or not shown for reasons of clarity;

30 Figure 3 is a perspective view of the duckbill adjusting mechanism;

Figure 4 is a plan view of the air jets;

Figure 5 is a front elevational view of the safety device; and

35 Figure 6 is a wiring diagram of the electrical connections.

Referring more particularly to the drawings, there is shown in Figure 1 a frame 10 on which is mounted a delivery manifold 11, which consists of a hopper 12 and two diverging ducts 13 and 14. Set in the manifold 11 is a diverter made up of a blade 15 attached to a shaft 16 rotatably mounted in the manifold and held in position by collars 17. On the end of this shaft is a clamp

40 block 18 adjustably engaging a diverter arm 19 which is held by friction in the clamp block. The diverter arm is pivotally attached by a clevis mount 20 to an air cylinder 21 secured to the manifold by a bracket 22 and a clevis mount 23. Suspended from each side of the frame is a scale mechanism 24 which carries a weigh frame

45 25. The scale mechanism is of conventional design and consists of fulcrum suspension rods 26 having one end secured to the frame by nuts 27 and the other end engaging twisters 28 mounted

on shafts 29. From these twisters are hung load suspension rods 30 which carry the weigh frame 25. On the ends of these shafts 29 are main levers 31 which are joined together by a link 32. At the ends of the main levers is a tie rod 33 joined to a beam 34 by a clevis mount 35. This beam is suspended from the frame by a clevis mount and tie rod 36, secured by nut 37. At the end of this beam a clevis mount 38 engages a steelyard 39 which is joined to a weigh head 40 secured to the frame. This weigh head is also of conventional design and serves as an indicator of the weight of the product being packaged.

Secured to the weigh frame are pillow blocks 41 through which is journalled a shaft 42 carrying a conveyor pulley 43. Also secured to the frame are take-up bearings 44 holding a shaft 45 also carrying a similar pulley 46. Around these pulleys is an endless conveyor belt 47. Also mounted to the weigh frame 25 are brackets 48 in which are carried a shaft 49 and a conveyor pulley 50 which serves to support the conveyor belt 47. On the end of the shaft 42 is a sheave 51 which is driven by a gearhead motor 52 through the belt 53. This motor is likewise secured to the weigh frame by means of a base 54 by which the tension on the belt can be adjusted by means of the adjusting screw 55 and nuts 56. Affixed to the weigh frame 25 are angle irons 57 which are in turn secured to a hopper 58 at the end of which is a duckbill 59. This duckbill is made up of a stationary jaw 60 and a moveable jaw 61.

The duckbill may be adjusted for bags of different size by means of the duckbill adjusting mechanism, more fully shown in Figure 3. This mechanism consists of a bar 62 with a plate 63 welded or otherwise secured to it. The plate 63 is in turn held by screws 64 to filler plates 65 affixed to the hopper 58. Attached to each end of the bar 62 are U-shaped members 66, holding adjusting screws 67, which carry bearing blocks 68 and engage threads in said blocks. These bearing blocks support a shaft 69 secured to the moveable jaw 61 of the duckbill. At the ends of the adjusting screws 67 are miter gears 70 which engage miter gears 71 on a shaft 72. At one end of this shaft is a hand wheel 73 for rotating the shaft and at the other end is a locking nut 74 for securing the shaft against rotation. Covering each U-shaped member are plates 75 which position the bearings and provide support for the shaft. Secured at the end of the shaft 69 is an arm 76 which is pivotally joined by a clevis mount 77 to an air cylinder 78 attached to the hopper by means of the bracket 79 and clevis mount 80 as shown in Figure 1.

Perforated rubber sheets 81 may be secured to the four corners of the duckbill to hold the bag more firmly and prevent it from slipping off the duckbill. A felt 82, shown in Figure 2, is mounted on the hopper by screws 83 and serves as a wiper blade against the conveyor belt. Over the conveyor belt is a cover 84 suitably fastened to the hopper and the weigh frame. A window 85 may be provided in the hopper so that the flow of the material in the hopper may be observed.

Secured to the frame 10 above the hopper 58 is an air cylinder 86, the piston rod of which carries a ram 87 which fits inside the hopper 58 with sufficient clearance to prevent its binding in its movement in the hopper. Also secured to the frame and in parallel relationship to the air cylinder are tubes 88 into which slide rods 70

also secured to the ram and which hold the ram in alignment with the hopper.

Secured to the frame 10 by bolts 90 are slotted members 91, which members carry an air jet mechanism 92. Referring to Figure 4, it will be seen that this air jet mechanism is provided with threads 93 at each end, which engage similar threads in the slotted members 91 so that the mechanism may be rigidly secured in position between such members. Caps or other suitable closures are used to seal such ends against the escape of air. This mechanism has nozzles 94, mounted on T's 95, a T 96 provided with bushings 97, and nipples 98 for joining the same together. The air is fed into the mechanism through the T 96. This air jet mechanism is positioned at the base and front end of the duct 13, as shown in Figure 2, and is adapted when the air is turned on to blow a stream of air which will sever the falling column and divert any product in the duct across and into an exhaust manifold 99 and away from the conveyor belt. This exhaust manifold is attached to the delivery manifold and the frame and can be provided with suitable means to recirculate the material and eventually carry it back into the top of the delivery manifold. This air jet mechanism affords a method of severing a falling column and obtaining an accuracy of weight which has not been heretofore possible with other machines packaging such materials. Although the machine illustrated employs an air jet for the cut-off, it will be understood that it also is possible with certain materials to use steam, water, or various other liquids or gases, all of which are referred to in the appended claims as "fluid."

To prevent the flow of the product through the duckbill at such time when no bag may be held thereon or when such bag may be torn, a safety device 100 is secured to the stationary jaw 60 of the duckbill. This safety device, as shown in Figure 5, consists of a strip of spring steel 101 anchored at its lower end in a bracket 102 secured to the duckbill. This spring steel is curved outward (see Figure 2) and slides in a slot in a plate 103 held to the duckbill by screws 104. The end of this spring steel is so adapted that pressure on its curved portion will cause the end of the spring steel to press against a button 105 of a switch 106 (LS#5—Fig. 6) mounted on the duckbill by screws 107. A suitable cover plate 108 is placed over the switch and held by screws 109.

The machine of the present invention is provided with various switches, the location and operation of which will be discussed in connection with the wiring diagram of Figure 6 and the operation of the machine during a packaging cycle. In the machine illustrated the material to be packaged is fed continuously into the hopper 12 of the delivery manifold and is alternately fed to duct 13 or 14 by the diverter 15. The units associated with each duct for weighing, filling, cutting off the feed and compressing are exactly the same in all respects. Although two units are shown in the machine illustrated in the drawings it will be understood that there may be a plurality of ducts and a plurality of such units. Figure 2 shows the flow of the material from the hopper, the dark arrows representing the flow to the bag being filled and the light arrows the material being diverted by the air jet mechanism. A foot switch 111 (foot SW#1—Fig. 6) is wired to and actuates the air cylinder 78, which rotates the shaft and causes the duck-

bill jaw 61 to collapse so that a bag can be placed in position on the duckbill. When the foot switch is released, the cylinder returns to its normal position, as shown in Figure 2, and holds the bag securely in place.

It has been found practical to adjust the dial indicator on the weigh head 40 so that it will initially show the weight desired in the bag. Then as the material flows to the conveyor, hopper and bag this indicator will move toward 0 and when the required amount is reached will read 0. A switch set in the weigh head at the 0 point is actuated by the indicator. By this arrangement it requires only a simple change of counterweights in the scale mechanism to set the scale for any weight desired and eliminates the necessity of moving the scale switch for every different weight.

The cycle of operation of the machine will be more clearly understood by referring to the wiring diagram of Figure 6. In this wiring diagram the electrical units associated with the left unit (duct 13) will be referred to as #1 and those associated with the right unit (duct 14) will be referred to as #2. Before describing the electrical system in detail, a brief general description of the system operation through one cycle will be given:

1. Closing main switch turns on air jet on open side of diverter.

2. Pressing the foot switches 111 to collapse the duck bill jaws permits placing bags on the duck bills, thereby turning off the air jet on open side of diverter.

3. Pushing Start button turns on both belt conveyors.

4. Normal starting position when current is turned on is:

(a) Diverter sending material to conveyor of #1 unit

(b) Both rams up

(c) Both duck bills open (bags in place).

5. When desired amount of material has accumulated on conveyor and in hopper and bag of #1 unit, the scale indicator closes the scale switch, actuating diverter and throwing feed over to #2 unit. This causes #1 air jet to go on and #1 timer to start.

6. When timer for #1 unit has passed set time

(a) #1 air jet goes off

(b) #1 ram compresses material in bag.

7. Bag is released from duck bill for #1 unit and new bag put on which re-cycles the #1 controls.

8. When conveyor, hopper and bag on #2 unit hold desired amount of material

(a) Diverter is thrown over to #1 unit

(b) #2 air jet goes on

(c) #2 timer starts.

9. After timer for #2 unit has passed set time

(a) #2 air jet is turned off

(b) #2 ram compresses material in bag.

10. After #2 ram has completed cycle, bag is released from duck bill for #2 unit and new one put on. This completes the cycle.

Referring further to Figure 6, it will be noted that the conveyor motors are provided with motor starters MCA and MCB and with overload protectors OLA1, OLA2, OLB1 and OLB2. In addition there are provided various control relays

which are made up of solenoids designated by RC— in a circle, which solenoids energize and actuate relay contacts designated by RC—. It will be further noted that some of these relay contacts are normally open while others are normally closed. The operation of such control relays will be clear from the detailed description of the electrical system operation which follows:

1. With the main switch and the motor switches closed the system is energized. Thus the normally closed contacts of relay RC2 energize air jet #1 valve solenoid turning air into the jets (92—Fig. 1) on #1 unit. The normally closed contacts of relay RC3 would energize air jet #2 valve solenoid except that circuit is broken by limit switch LS#2, which is the switch for duct 14 (Fig. 1) actuated by the diverter arm. Foot switches SW#1 and SW#2 (111—Fig. 1) are direct connected to duck bill valve solenoids which, when energized, actuate the air cylinders on the duck bills and permit bags to be slipped on. Start button on system control energizes motor starters MCA and MCB and starts belt conveyors. With bags in place the normal start is made and all relays and circuits are de-energized, except relays RC2 and RC3 which are energized, cutting out air jet circuits.

2. When desired amount of material has caused the scale indicator on the weigh head 40—Fig. 1) associated with unit #1 to go to 0 point, scale switch SW#1 closes, energizing relay RC12. The single contact of RC12 closes, thus energizing relay RC5. RC5 has an overlap, one normally open contact closing and holding relay and one normally closed contact opening and breaking circuit to RC12. This also completes circuit to and starts timer T-1 working.

(a) One normally open contact of RC5 closes and energizes RC14, one contact of which closes and holds RC14, the other contact closes and energizes solenoid of diverter valve. This actuates the air cylinder (21—Fig. 1) and diverter closes material flow to conveyor of #1 unit and starts flow to conveyor of #2 unit.

(b) Another normally open contact of RC5 closes and completes circuit to air jet #1 solenoid causing #1 air jet to go on. The remaining normally open contact of RC5 closes and completes circuit to air jet #2 solenoid causing #2 air jet to go on unless there is a bag in place on #2 duck bill. With bag in place the bag control limit switch LS#6 closes, energizing relay RC3 and breaking circuit to #2 air jet.

3. When timer T-1 has passed set time a clutch throws over and relay RC8 is energized. One normally closed contact is opened and #1 air jet shuts off. One normally open contact closes, completing circuit to ram #1 valve solenoid which, when energized, actuates the air cylinder (86—Fig. 1) and causes the ram (87—Fig. 1) to come down, compressing material into the correct and predetermined level in the bag. The ram rod (89—Fig. 2) strikes and closes limit switch LS#3 (112—Fig. 2) at bottom of stroke, thus energizing relay RC9. One normally open contact closes and keeps it energized and one normally closed contact opens, which de-energizes ram solenoid and ram returns to top of stroke.

4. Filled bag is released from duck bill by stepping on foot switch SW#1 which energizes duck bill #1 valve solenoid collapsing duck bill. Stepping on foot switch SW#1 also energizes relay

RC6 whose normally closed contact opens, which breaks circuit to and de-energizes RC5, RC8 and RC9. Releasing bag from duck bill also opens bag control limit switch LS#5 (106—Fig. 5) de-energizing relay RC2, which closes contacts, partially making circuit to air jet #1 solenoid. Stepping on foot switch SW#1 thus cycles left side of machine. When new bag is put on duck bill and foot switch released, relay RC6 is de-energized. Bag closes limit switch LS#5 energizing relay RC2 which partially closes circuit to air jet #1 solenoid.

5. When desired amount of material has caused scale indicator on the weigh head associated with #2 unit to go to the 0 point, scale switch SW#2 closes, energizing relay RC13. The single contact of RC13 closes, energizing relay RC4. RC4 has an overlap; one normally open contact closing and holding relay and one normally closed contact opening and breaking circuit to RC13. This also completes circuit to and starts timer T-2 working.

- (a) One normally closed contact of RC4 opens and breaks circuit to relay RC14 deenergizing diverter valve solenoid and causing diverter to stop flow of material to conveyor associated with #2 unit and start flow to conveyor of #1 unit;
- (b) Another contact of RC4, normally open, closes and completes circuit to air jet #2 solenoid causing #2 air jet to go on. The remaining normally open contact of RC4 closes and #1 air jet goes on unless there is a bag in place on #1 duck bill. With bag in place the limit switch LS#5 (106—Fig. 5) closes, energizing relay RC2 and breaking circuit to #1 air jet.

6. When timer T-2 has passed set time a clutch throws over and relay RC10 is energized. One normally closed contact is open and #2 air jet shuts off. One normally open contact closes, completing circuit to ram #2 valve solenoid and causing ram to come down compressing material in bag. Ram closes limit switch LS#4 at bottom of stroke, thus energizing relay RC11. One normally closed contact is opened, which de-energizes ram solenoid and ram returns to top of stroke.

7. Filled bag is released from duck bill by stepping on foot switch SW#2 which energizes duck bill #2 valve solenoid collapsing duck bill. Stepping on foot switch SW#2 also energizes relay RC7 whose normally closed contact opens, which breaks circuit to and de-energizes RC14, RC11 and RC10. Releasing bag from duck bill also opens limit switch LS#6 de-energizing relay RC3, which closes contacts, partially making circuit to air jet #2 solenoid. Stepping on foot switch SW#2 thus cycles right side of machine. When new bag is put on duck bill and foot switch released, relay RC7 is de-energized. Bag closes limit switch LS#6 energizing relay RC3 which partially closes circuit to air jet #2 solenoid. The cycle is thus complete and system is in same condition as at start of cycle.

This machine and the electrical system associated with it are so designed as to provide various safety features in the operation. For example, if material is delivered to either conveyor and a bag is not in position to receive it, the bag control safety device (shown in Fig. 5) secured to the stationary jaw of the duck bill turns on the air jet on that particular unit of the machine which blows the material away from the conveyor and into exhaust manifold (99—Fig. 2).

Furthermore, if at any time a bag receiving material should split or tear and fall off the duck bill, this safety device would operate in the same manner to prevent further flow of the material. Likewise, if the diverter should jam or fail to move the air jet would go on and prevent further flow of material.

As heretofore pointed out, the machine of the present invention compresses the material to a predetermined level or load line in the bag, thereby permitting the use of a bag of a size merely sufficient to hold the material after it has been compressed. However, prior to compression the predetermined amount of material will not fit into the bag and it is necessary to provide a reservoir above the predetermined level or load line of the bag. This is accomplished, as will be noted in Figures 1 and 2, by making the hopper 58 of sufficient length to hold above the bag all the material which will not fit into the bag. The packaging of loose rockwool will serve as an illustration. It is customary in that industry to package 40 lbs. of such material in a bag. When this amount has been run through the machine of the present invention, but has not been compressed, approximately 50 to 60% of the material fits in the bag up to the predetermined level or load line of the bag and the remaining 50 to 40% is held by the hopper and duckbill above the load line. The ram then compresses all the material into the bag below the load line. For different materials and even different types of rockwool the amount of material which the bag will hold before compression will vary, but in every case the hopper must be of sufficient length to receive a substantial quantity of the material which is to be compressed within the bag. The minimum length of the hopper can be simply determined by measuring the column of material which remains above the load line of the bag when the predetermined weight has been reached but the material has not yet been compressed. To assure sufficient capacity in the hopper the minimum length of the hopper should be at least one half as long as the distance from the load line to the bottom of the bag. Of course the hopper can be made longer than necessary to accommodate the excess for all types of material.

It will be understood that the term "bags" where used in the specification and claims includes cartons, containers and other receptacles suitable for packaging material referred to.

Although the machine of the present invention is especially useful and satisfactory and has distinct advantages over other machines in the packaging of fibrous materials such as rockwool and the like, it will be understood that the machine may also be very efficiently used in the packaging of pulverulent, granular or other similar materials.

It will thus be seen that the objects herein set forth may readily and efficiently be attained, and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described and all features of the scope of the inven-

tion which, as a matter of language, might be said to fall therebetween.

Having described my invention, what I claim as new and desire to secure by Letters Patent is:

1. A packaging machine for filling bags comprising bag holding means, a conveyor positioned to discharge material into a bag on the bag holding means, a weighing scale carrying the conveyor, holding means and bag, means for feeding material to the conveyor, means controlled by the scale in response to said predetermined weight for cutting off the feed to the conveyor, a jet mechanism positioned adjacent the column of material falling to the conveyor and adapted to direct a stream of fluid under pressure against the falling column for severing said column and preventing the material from reaching the conveyor, a switch-controlling tension member mounted on the bag holding means and cooperating with the bag on the holding means, a switch actuated by the bag against the tension member, and means controlled by the switch for turning on the jet mechanism and severing the feed to the conveyor if no bag or a defective bag is on the holding means.

2. A packaging machine for filling bags with a predetermined weight of compressible material compressed to a predetermined load line in the bag comprising a conveyor, a hopper positioned to receive material from the conveyor, said hopper having a length at least one-half as long as the distance from the predetermined load line to the bottom of the bag to serve as a reservoir for excess material above the load line of the bag prior to compression, a duckbill secured to the hopper to support the bag on the hopper, a weighing scale carrying the conveyor, hopper, duckbill and bag, a duct for feeding the material to the conveyor, a ram cooperating with the hopper to compress the material into the bag, and means controlled by the scale in response to a predetermined weight for cutting off the feed to the conveyor and actuating the ram.

3. A packaging machine for filling bags with a predetermined weight of compressible material compressed to a predetermined load line in the bag comprising a hopper for feeding material into the bag, a bag holder to hold the bag on the hopper, a conveyor positioned to discharge material into the hopper, said hopper having a length at least one-half as long as the distance from the predetermined load line to the bottom of the bag to serve as a reservoir for excess material above the load line of the bag prior to compression, a weighing scale carrying the conveyor, hopper, holder and bag, means for feeding the material to the conveyor, a ram cooperating with the hopper to compress the material into the bag, and means controlled by the scale in response to a predetermined weight for cutting off the feed to the conveyor and actuating the ram.

4. A packaging machine for filling bags with a predetermined weight of compressible material compressed to a predetermined load line in the bag comprising a hopper for feeding material into the bag, a bag holder to hold the bag on the hopper, a conveyor positioned to discharge material into the hopper, said hopper having a length at least one-half as long as the distance from the predetermined load line to the bottom of the bag to serve as a reservoir for excess material above the load line of the bag prior to compression, a weighing scale carrying the conveyor, hopper, holder and bag, means for feeding the material to the conveyor, means for com-

pressing the material into the bag, and means controlled by the scale in response to a predetermined weight for cutting off the feed to the conveyor and actuating the compressing means.

5. A packaging machine for filling bags with a predetermined weight of compressible material compressed to a predetermined load line in the bag, comprising a belt conveyor, a hopper positioned to receive material from the conveyor, said hopper having a length at least one-half as long as the distance from the predetermined load line to the bottom of the bag to serve as a reservoir for excess material above the load line of the bag prior to compression, a bag holder to hold the bag on the hopper, a weighing scale carrying the conveyor, hopper, holder and bag, a duct for feeding the material to the conveyor, means for compressing the material into the bag, and means controlled by the scale in response to a predetermined weight for cutting off the feed to the conveyor.

6. A packaging machine for filling bags, comprising bag holding means, a conveyor positioned to discharge material into the bag on the bag holding means, a weighing scale carrying the conveyor, holding means and bag, means for feeding material by gravity to the conveyor, a jet mechanism positioned adjacent the column of material falling to the conveyor and adapted to direct a stream of fluid under pressure against the falling column for severing said column and preventing all material over a predetermined weight from reaching the conveyor, and means controlled by the scale in response to said predetermined weight for cutting off the feed to the conveyor and turning on the jet mechanism.

7. A packaging machine for filling bags, comprising bag holding means, a hopper for feeding material into the bag on the bag holding means, a conveyor positioned to discharge material into the hopper, a weighing scale for carrying the conveyor, hopper, holding means and bag, means for feeding material by gravity to the conveyor, means positioned adjacent the column of material falling to the conveyor for severing said column and preventing all material over a predetermined weight from reaching the conveyor, said severing means comprising a mechanism for directing a stream of fluid under pressure against the falling column, and means controlled by the scale in response to said predetermined weight for cutting off the feed to the conveyor and turning on the said mechanism.

8. A packaging machine for filling bags comprising bag holding means, a conveyor positioned to discharge material into the bag on the bag holding means, a weighing scale carrying the conveyor, holding means and bag, means for feeding material by gravity to the conveyor, means positioned adjacent the column of material falling to the conveyor for severing the falling column and preventing all material over a predetermined weight from reaching the conveyor, said severing means comprising a mechanism for directing a jet of air under pressure against the said column, and means controlled by the scale in response to said predetermined weight for cutting off the feed to the conveyor and turning on the said mechanism.

9. A packaging machine for filling bags comprising bag holding means, a conveyor positioned to discharge material into the bag on the bag holding means, a weighing scale carrying the conveyor, holding means and bag, means for feeding material to the conveyor, a jet mecha-

nism positioned between the conveyor feeding means and the conveyor and adapted to direct a stream of fluid under pressure against the column of material feeding to the conveyor for severing said column and preventing all material over a predetermined weight from reaching the conveyor, and means controlled by the scale in response to said predetermined weight for cutting off the feed to the conveyor and turning on the jet mechanism.

10. A packaging machine for filling bags comprising bag holding means, a hopper for feeding material into the bag on the bag holding means, a conveyor positioned to discharge material into the hopper, a weighing scale carrying the conveyor, hopper, holding means and bag, means for feeding material to the conveyor, a jet mechanism positioned between the conveyor feeding means and the conveyor and adapted to direct a stream of fluid under pressure against the column of material feeding to the conveyor for severing said column and preventing all material over a predetermined weight from reaching the conveyor, and means controlled by the scale in response to said predetermined weight for cutting off the feed to the conveyor and turning on the jet mechanism.

11. A packaging machine for filling bags comprising bag holding means, a hopper for feeding material into a bag on the bag holding means, a conveyor positioned to discharge material into the hopper, a weighing scale carrying the conveyor, hopper, holding means and bag, means for

feeding material to the conveyor, means controlled by the scale in response to said predetermined weight for cutting off the feed to the conveyor, a jet mechanism positioned adjacent the column of material falling to the conveyor and adapted to direct a stream of fluid under pressure against the falling column for severing said column and preventing the material from reaching the conveyor, a tension member mounted on the bag holding means and cooperating with the bag on the bag holding means, means actuated by the pressure of the bag against the tension member to turn off jet mechanism if a bag is exerting pressure against the tension member.
